TUNING DEVICE

Le Roy J. Leishman, Los Angeles, Calif.

Application August 3, 1940, Serial No. 350,355

15 Claims. (Cl. 74—10.39)

1 The invention herein described pertains to means for turning rotatable shafts to predetermined angular positions, particularly where the control shafts are associated with the tuning mechanism of radio apparatus and the like. Among its objects are: to provide means for rotating such control shafts through any required angle without the use of split-gears or other special means to eliminate lost motion; to reduce the size of such a shaft-positioner, or tuning device, by making it possible for all reciprocating parts to move in substantially the same directions; to provide simple means for setting the required adjustable elements; to supply the demand for a push button operated tuner that will be accurate and easily constructed; and to make it possible to set such tuners from the outside of the set, or from the push buttons themselves. Still other objects will appear as the description proceeds.

In the drawings:

Fig. 1 is an end view of one form of my device with one end plate removed to show the mechanism.

Fig. 2 is a plan view, partly in section taken on line 2—2 of Fig. 1, showing the construction of one form of setting mechanism applicable to the device of Fig. 1.

Fig. 3 is a cross section of the tuning shaft of Fig. 2, showing the key-way, the washer that fits this key-way; and, in dotted lines, a spacer behind the washer.

Fig. 4 shows another form of push button for automatic tuners, in which the set screw of the adjustable element may be reached when in the tuned-in position by inserting a screw-driver through the hollow stem of the push button itself.

Fig. 5 is a sectional view taken substantially on line 5—5 of Fig. 4.

Fig. 6 shows a means for setting and manually tuning the device of Figs. 1 and 2 from the front of the set.

Fig. 7 shows another means for setting and manually tuning the device of Figs. 1 and 2 by the use of discs protruding through the escutcheon.

Fig. 8 shows a third means for setting the device of Figs. 1 and 2 from the front of the instrument.

Fig. 9 is a modified form of the device of Figs. 1 and 2, in which the adjustable parts are on the push-button, or operating means, rather than on the rotatable control shaft.

Fig. 10 is a plan view of Fig. 9 with various associated parts added.

Fig. 11 is a sectional view of the parts mounted

on the push button of the device of Fig. 9, and is taken on line 11—11 of Fig. 9.

Fig. 12 shows other details of the push button construction of the device of Fig. 9, and is in part a sectional view taken on line 12—12 of Fig. 9.

Fig. 13 is a section taken on line 13—13 of Fig. 15, showing a modification of the species of Figs. 1 and 2, the manually movable operating member and the racks of this modification moving rectilinearly instead of arcuately.

Fig. 14 is a section taken on line 14—14 of Fig. 15, and shows one of the operating plungers in tuned-in position against the rectilinearly movable racks.

Fig. 15 is a plan view of a tuner embodying this modification.

Fig. 16 is a detail of Fig. 15.

Fig. 17 is a section taken on line 17—17 of Fig. 19, showing how the species of Figs. 9 to 12 may be modified so that the racks have rectilinear instead of rotary motion.

Fig. 18 is an other view of the mechanism of Fig. 17, showing the plunger assembly in the tuned-in position.

Fig. 19 is a plan view of a tuner embodying this modification.

Fig. 20 is a detail of Fig. 19.

Fig. 21 illustrates a modification of the device of Figs. 17, 18 and 19 in which the racks on the plunger are replaced by an angularly adjustable tappet member.

In Fig. 1, gear A is shown mounted on shaft B. It is fixed in a predetermined angular position with relation to shaft B by means of an arrangement that will be described in connection with Fig. 2. Gear segment C is free to turn on shaft E, and meshes with gear A. Segment D of an internal gear also meshes with gear A and is freely pivoted on shaft E. The operating arm F, like the gear segments, is also free to turn on shaft E, but is normally held in an inoperative position with projection K against bumper M by spring J, attached to projection K and rod L. Bumper M may be a tube of resilient material, such as rubber, mounted on a rod N, but many other suitable expedients will suggest themselves to those skilled in the art. Operating arm F has an arcuate section G extending through escutcheon O on the front of the set, and a button or other convenient top H is mounted on the end of section G, which thus forms the stem of a push-button. Arm F has a lip P turned at right angles to the rest of the arm to engage the edges of gear segments C and D. It will be seen from the description thus far given that regardless

55 of the description thus far given that regardless

of the angular position of gear A within approximately 180 degrees, the pressing of button H will cause arm F to engage whichever gear segment happens to be the nearest, and the further movement of arm F will turn gear A and the other gear segment until the latter collides with lip P on arm F, at which time the parts will be in the position shown in full lines in Fig. 1. This is the "tuned-in" position to which arm F always returns these parts, including gear A. Gear A, of course, may occupy any angular position with respect to shaft B, according to its original setting, to be explained later.

Stem G has two indentations or notches, the forward notch having a rounded shoulder T at the rear side of the notch, and the rear notch having a straight shoulder S at the forward side of the notch. These notches actuate the latch-bar Q, which has a pivot V, Figs. 1 and 2. The latch bar is held against the stems G of all the operating arms, there being a plurality of sets of such arms and segments like those previously described all pivotally mounted on shaft E.

The gear segments in each set cooperate and mesh with a gear identical to gear A, such additional gears being designated in Fig. 2 by the reference characters A₂, A₃ and A₄.

When stem G is at the end of its operating stroke, at the "tuned-in" position shown in Fig. 1, the end R of latch bar Q slips into the rear notch in the stem and engages edge S of the notch, thus preventing spring J from returning the operating arm to its normal or rest position. Shaft B is thus locked in the angular position to which it was turned when button H was depressed, and if shaft B is operatively connected to the tuning shaft of a radio set, the receiver is consequently locked at a definite setting.

The pressing of another button releases the one that is locked down, as the forward and rear notches in all the stems are spaced in such a manner that the rear shoulders of the forward notches all rest just behind the point R of the forward end of the latch bar. Shoulder T₂ in the forward notch of stem G₂ is shown in this position. When button H₂ is pressed, this shoulder will engage the latch bar, forcing it out of the rear notch in stem G, thus causing stem G and arm F to flip back to the rest position under action of spring J. When button H₂ has been pressed as far as possible, the edge S₂ in the rear notch of stem G₂ will be engaged by the latch bar in the manner just described with reference to stem G.

Fig. 1 shows segment D₂ in its extreme forward position and segment C₂ at the opposite end of its stroke. When button H₂ is depressed, arm F₂ will first engage the forward end of segment D₂, turning gear A₂ (not shown) in a counter-clockwise direction, thus bringing segment C₂ forward. This motion continues until the forward edge of segment C₂ strikes arm F₂, preventing further motion.

In order to show these segments in an opposite extreme of their possible motion, Fig. 1 shows a third set in dotted lines, segment C_a and segment D_a. These particular segments do not appear in Fig. 2, and are shown in this manner in Fig. 1 merely to simplify the illustration and the explanation.

The means and method for setting the A gears in predetermined angular positions will now be explained. The arrangement is much the same as that shown and described in the Vasselli Patent No. 1,846,289, excepting that I have made

novel provisions for completing the setting operation without having to get inside the set. As shown in Figs. 1, 2 and 3, shaft B has a keyway X. A plurality of washers Y, Fig. 3, are each provided with an inwardly extending tang 6 to fit the key way. One of these washers is placed on each side of each A gear, as shown in Fig. 2; and the various groups, each consisting of two washers with a gear between them, are spaced on shaft B by means of spacers or collars Z, as shown in the figure. Collar Zb is a longer tube than the others, and passes through end plate 7, in which it is journaled, and also through a hole 8 in the side panel 9 of the radio cabinet. Shaft B extends past the end of tube Zb, and has a threaded end to accommodate the tapped hole in knob 10, which is mounted thereon. Another knob 11, having a pin 51 to fit the keyway, is mounted on shaft B next to knob 10. Between knob 11 and the outer end of collar Zb is mounted a cup-shaped spring washer 12.

The gear segments and operating arms mounted on shaft E must be grouped as shown in Fig. 2, and the groups spaced by spacers Z_a to hold the gear segments in mesh with the gears on shaft B.

In the form shown in Fig. 2, shaft B is the shaft of condenser 13, shown diagrammatically, mounted on end plate 14 of the automatic tuner assembly. A collar 15, having a set-screw or pin 16, is mounted on shaft B just inside of end plate 14. It will now be evident that all the parts carried by shaft B may be clamped in position by means of knob 10. If this knob and shaft B have right-handed threads, a slight rotation of this knob to the right will turn shaft B to the limits provided by the condenser, but the further rotation of knob 10 will press knob 11 against the spring washer 12, finally flattening it out, and tightening all the parts on the shaft against the stop-collar 15.

To set a tuner of this kind, knob 10 is loosened by rotating it to the right, thus permitting the spring-washer 12 to expand. This releases most of the side pressure on the A gears, the only pressure remaining being that of the spring-washer. The button that is to be set to tune in a predetermined station, say button H, is now pressed down and held there, either by the operator's finger or the latch-bar. The associated segments and gear A are now prevented from turning, but shaft B may be turned inside of gear A. The desired station is next tuned in by means of knob 11, which is keyed to the shaft. This causes the shaft and gear A to assume a definite angular relationship that is individual to the station that is tuned in. Another button may now be pressed down and a different station tuned in in like manner. The setting of the gear previously set will not be disturbed, because the keyed washers permit everything on the shaft to turn as a single unit, excepting the gear that is locked in position by the depressed button, and its relative movement with respect to the shaft cannot be frictionally transmitted to other parts on the shaft because of the intervention of the keyed washers which will not move angularly. After all the A gears have been set in this manner, knob 10 is again tightened on the shaft, locking all the gears in the angular positions to which they were individually adjusted. It will now be obvious that the subsequent pressing of any button will tune in the station that was tuned in while the button was originally depressed during the setting operation.

Fig. 4 shows another push-button arrangement in which the adjustable element, like the A gears of Figs. 1 and 2, is mounted on the shaft. In this construction, however, the adjustable element A is affixed to the rotatable control shaft B by means of a set-screw 16 which may be reached in the tuned-in position by removing the cap H and the index tab 19 from the push-button and inserting a screw driver through the hollow stem 24. The entire push-button assembly consists, in addition to the parts already mentioned, of a cross piece 26 and a pair of legs 27 having reduced ends 23, thus forming shoulders 25 to take the thrust of expansion springs J that abut against end-piece 22 which is apertured to form guides to permit the longitudinal movement of the reduced ends 23.

The cap H of the device of Fig. 4 has a window 18 in the end through which call letters on the station index tab 19 may be read. This index tab rests on the round end member 17 into which the hollow tube 24 is tightly pressed. The cap H may be screwed to end member 17, or the two may be suitably shaped so that the cap will slip on and off.

In addition to the apertures provided in end-piece 22, the movement of the assembly is also guided by an aperture in the guide member 28. The escutcheon 21 has a large hole 29 to permit the stem to pass through without any possibility of binding. The continuous lines in the figure show the assembly and the positionable element in the tuned-in position. In broken lines, these same parts are shown as the cross piece 26 is pushing the positionable element toward the tuned-in position. A cross-section of certain of these parts is shown in Fig. 5, which is a view taken on line 5-5 of Fig. 4. The various parts may be identified by the reference characters.

Fig. 6 illustrates a modification of the setting mechanism shown in Fig. 2, in which all the setting operations may be performed from the front panel. The gears, spacers, washers and the shaft all perform the same function and are formed in the same manner as the parts bearing the corresponding reference characters in Fig. 2. The variation is in collar 36 and the parts lying to the right of it. Collars 34 and 36 each have square shoulders on both sides of one end to receive the ends of the spring clamps 29 and 29a, as shown in the drawing. Spring clamp 29a has a hole to admit the reduced end of the long adjusting screw 31, which has a shoulder 32 adapted to press against clamp 29a. The reduced end of 31 then passes through hole 37 in shaft B, and the extreme threaded end 33 of screw 31 is screwed into a threaded hole in spring clamp 29, which has a reinforcing section 30, also threaded.

The right end of shaft B carries wheel 38, attached to the shaft by screw 39. Wheel 38 has a beveled edge, as indicated. A bracket 49, attached to end plate 7 by screws 50, carries a bushing 43 through which passes a shaft 49 having a shoulder 41 and carrying a wheel 42 that has a periphery of good frictional characteristics and which, therefore, may be formed of rubber. Shaft 40 is surrounded by an expansion spring 45 abutting against the bushing 43 and exerting its pressure against pin 46, thus urging shaft 40 in a direction away from the bevel wheel. The outer end of shaft 40 carries a knob 47, preferably tapered somewhat as shown, by means of which shaft B may be manually rotated. Spring 45 is very light, and due to the taper of knob 47, the tension of the spring is almost overcome by the

manual pressure required to get a good hold on the knob. When wheel 42 is in contact with the beveled edge of wheel 38, the shaft B is readily rotated by knob 47.

Collars 34 and 36, the clamping springs 29 and 29a, hole 37 and screw 31 are so coordinated with respect to the tuning condenser and the indicating scale that screw 31 is in alignment with hole 48 in the escutcheon at one of the extremes of motion of the condenser. To set a tuner so equipped, shaft B is turned as far as it will go in the required direction so that screw 31 will be accessible through hole 48. Screw 31 is then loosened by means of a screw driver. With the clamping tension thus removed from the A gears, it will be obvious that the setting operations may be performed in the manner described with relation to Fig. 2. After all the desired stations have been tuned in with the proper buttons depressed, the manual knob is again turned to the limit of motion that brings screw 31 behind hole 48, and the screw is again tightened, thus clamping the A gears in the positions to which they have been adjusted. These A gears are part of an apparatus such as that shown in Figs. 1 and 2, and Fig. 6, for the sake of clearness, therefore merely shows the variations from the embodiments of the invention previously described.

Fig. 7 illustrates a modification in which the knobs 10 and 11 of Fig. 2 are replaced by discs 10 and 41, protruding through openings 48 and 48a respectively in the escutcheon 21, thus permitting the setting operation to be performed from the front of the set. Longitudinal movement of shaft B is prevented by collar 15 and the hub of disc 41 mounted on opposite sides of plate 14 and held in place by set screws 16 and 51 respectively. Gears A, A2 and A3 are mounted on the shaft between keyed washers Y, as described in the explanation of Fig. 2. Spacers Z perform the same function as in the devices of previously described figures. Disc 10 is attached to a hub 64 having a reduced end 65, journaled in end plate 7. Hub 64 has a threaded center hole for mounting the hub and disc on the threaded end of shaft B. If disc 10 is rotated after shaft B has reached the limit of its movement in either direction, the disc of course moves longitudinally within certain limits on shaft B as it turns on the threads on the shaft. Aperture 48 in the escutcheon must be sufficiently wide to permit this necessary longitudinal movement of disc 10. As hub 64 moves longitudinally under these conditions, it either increases or decreases the pressure on the keyed pressure collar 52, varying the tension on spring 12, which serves the same function as spring 12 in the device of Fig. 2. It will thus be evident that the positionable gears A, A2 and A3 may be loosened for angular adjustment on shaft B by turning disc 10 by means of a downward movement of the thumb on the portion of its periphery that protrudes through hole 48. These gears cooperate with toothed operating members, omitted from the figure for the sake of clearness, and may be individually held against rotation by holding down the associated button. With a gear immobilized in this manner during the setting operation, the desired station is tuned in by means of disc 41, which turns with the shaft.

Fig. 8 shows another arrangement for setting such a tuner from the front of the cabinet. Shaft B may be restrained from longitudinal movement by means of collars, or by reduced ends, such as end 59 in end plate 7. The other

end of the shaft, of course, has similar provisions for preventing end thrust. Collar 63 is threaded to turn on the threaded portion of shaft B, and has a pair of pins 53 and 53a adapted to slide in holes 54 and 54a respectively in gear 55, adapted to turn freely on the reduced portion 58 of shaft B, but held against longitudinal movement by collars or pins 56 and 57. End plate 7 carries a bracket 49 in which is journaled a shaft 40. A bevel-gear 60 is affixed on shaft 40 by means of screw or pin 61. A spring 45, abutting against one end of bracket 49, presses on pin 46 in shaft 40, thus urging the shaft in a direction that normally keeps the hub of gear 60 against the bracket. Shaft B has a hole 37 in the reduced portion 58, and when the operator presses on knob 10, attached to shaft 40, the reduced end 62 of shaft 40 moves into hole 37, thus preventing the rotation of shaft B. Before shaft B can be immobilized in this manner, it must first be turned to as far as it will go in one direction so that hole 37 will be properly aligned to receive end 62 of the operating shaft. When knob 10 is thus pressed toward shaft B, against the action of spring 45, not only is shaft B prevented from turning, but gear 60 is caused to mesh with gear 55 so that member 63 may be turned on shaft B by rotating knob 10. Knob 10 thus controls the tension on spring washer 12, which acts as does the corresponding washer in previously described figures.

Figs. 9, 10, 11 and 12 illustrate a modification of the device of Figs. 1, 2 and 3. On shaft B, just inside of end plates 7 and 14, are mounted gears A and A2, as shown in Fig. 10. In the corresponding positions on shaft E are mounted two sets of gear segments, C and D at one end, and Cb and Db at the other. External gear segment C and internal gear segment D both mesh with gear A, and external gear segment Cb and internal gear segment Db both mesh with gear A2. The external segments C and Cb are connected together by means of rod 72, and rod 73 is connected to both internal gear segments D and Db by means of rivets 75 and 75b respectively. The internal gears and connecting rod 72 turn as a unit, as do also the two external gear segments and connecting rod 73, and as a consequence shaft B may be made to assume different angular positions by varying the relative positions of these reciprocating rods. The various operating arms F, F2, etc., are therefore equipped with adjustable elements that may be fixed in predetermined positions for moving the connecting rods 72 and 73 to the positions required to bring gears A and A2 and shaft B to the desired preselected angular positions. Fig. 1 shows a set of these adjustable elements associated with operating arm F. As pictured in Fig. 11, arm F carries a boss 69 which journals a short shaft 67, to one end of which is connected a gear 66. The opposite end of shaft 67 is provided with a nut or shoulder 68. Internal gear segment U2 and external gear segment U1 both mesh with gear 66, carried by arm F, as shown in Fig. 9. Spring J, attached to rod L, holds arm F in a normal inoperative position with the extension K resting against rubber tube M on rod N.

The operation of this form of the invention can probably best be described by first explaining the provisions for setting the keys, as well as the setting operation itself. As shown in Fig. 12, the operating stem G terminates in a cap H which is removable from the sub-button 17. Upon the removal of this cap and the index tab 18, 76

which the cap ordinarily holds in place beneath window 19, the head 76 of the long set-screw 10 may be reached by a screw driver. The outer end of this screw has a supporting guide 71, carried by stem G, and the lower end is threaded to fit a tapped hole in boss 69. When this screw is loosened, shaft 67 and the attached gear 66 are free to rotate. Segments U1 and U2, meshing with gear 66 are therefore also free to move. With this gear assembly thus free to turn, the sub-button 17 is pressed as far down as it will go, bringing gear 66 and extension K to the positions in which they are shown in dotted lines and indicated by 66a and Ka respectively. The forward ends of segments U1 and U2 now remain in contact with rods 72 and 73 respectively. This position for the three elements last named is indicated in dotted lines, the reference characters U2a, 72a and 73a being used respectively for these parts. The corresponding position for segment U1 has been omitted for the sake of clarity. While the button is being held down, the usual manual knob is used to tune in the station that is henceforth to be tuned in by this button. The drive from the manual knob may be of the type illustrated in Fig. 10, in which shaft 40 is assumed to be connected to the tuning knob. This shaft carries a pulley 78, to which are attached cords 79 and 80, each extending partially around drum 77 in opposite directions in a manner well known in the art. This arrangement is shown for cord 79, which passes around drum 77 from the rear and is attached at point 81. It will be evident from the figure and this description that the rotation of shaft 40 will also cause the rotation of shaft B, attached to condenser 13 and carrying gears A and A2. The consequent rotation of these gears moves the meshing gear segments and the attached rods 72 and 73. Any movement of these rods during the setting operation while the operating button is depressed, causes a corresponding movement of gear segments U1 and U2 and the intervening idler gear 66. After the desired station has been tuned in as perfectly as possible, set-screw 10 is tightened, thus preventing shaft 67 and gear 66 from turning, and then the index tab 18 and cap H are replaced. When the operating button is released, spring J returns arm F to its rest position with extension K against bumper M. With segments U1 and U2 thus withdrawn from the range of movement of bars 72 and 73, the shaft B, condenser and other associated movable parts may be turned to any desired position; but when button H is again pressed, segments U1 and U2, locked in their relative position by the action of the set-screw on shaft 67 and gear 66, will move rods 72 and 73 to the positions that they occupied in the original setting operation.

A plurality of operating arms like arm F are of course mounted on shaft E, and the adjustable assemblies that they carry are individually set in the manner above described so that the pressing of the different buttons brings in different stations. These arms are conveniently spaced on shaft E by spacers Za. Fig. 10 shows two of these operating arms F and F2, having stems G and G2, respectively, mounted on shaft E.

The gear segments of Figs. 1, 2, 9 and 10, may of course be replaced by longitudinally movable racks. When the device of the first two figures is modified in this way, stem G becomes a straight bar moving in guides similar to those

provided in the device of Fig. 4; and a cross-bar like members 26, Fig. 4, or lip P, Figs. 1 and 2, engages the ends of racks corresponding to gears C and D.

Such a modification is shown in Figs. 13 to 16, inclusive, in which the shaft B carries a plurality of angularly adjustable gears A, A2 and A3, as in Fig. 2. Keyed washers Y, Fig. 3, are provided on either side of these gears, and the washers cooperate with a key-way in the shaft as illustrated in Fig. 2. These gears are clamped in adjusted angular position on the shaft by means of a gear and nut arrangement like that shown in Fig. 8. Fig. 8 shows a hole 37 in shaft B to receive an extension 62 on shaft 40 for immobilizing the shaft against rotation when the manual knob turns shaft 40 while gear 60 is meshing with gear 55. This hole 37 and shaft extension 62 are of course unnecessary when their function is not required due to the provision of other stops (such as pin 14 and stopper 31 shown in Fig. 4 of my abandoned application Serial No. 253,174, filed January 27, 1939) or when limiting stops are provided on the variable condenser, as is usually the case. The optional hole 37 and shaft extension 62 are therefore omitted from Fig. 15, it being assumed that shaft B is connected to the conventional type of condenser which provides its own stops. Shaft B will thus stop turning in either direction when the condenser reaches the end of its permitted angle of rotation. Further turning of shaft 40, Fig. 15, will thus cause gear 55 to turn relative to the shaft when shaft B has reached the limit of its movement, thus causing nut 63 to move longitudinally along shaft B so as to clamp the gears A in adjusted position, or to release the gears from all tension except that provided by the spring washer 12 if the nut has turned in an opposite direction. This action has been more fully described in connection with Fig. 8.

When the reciprocating toothed members move longitudinally as in the modification being described, racks R1 and R2 replace the gear segments C and D of the species of Figs. 1 and 2. These racks move in ways or guides in cross-members 82 and 83, the ways themselves being mere perforations 84, as shown in cross-member 82, Fig. 16.

For operating the translationally movable racks, the operating member takes the form of a rectilinearly movable plunger such as G_a, Fig. 13. Plunger G_a moves in a slot in the front cross-member 85, and its lower arm 86 moves in a similar slot 87 (Fig. 16) in cross-member 82. Compression spring J_a yieldingly holds the plunger G_a in its rest position against bumper M_a. When push button H₁ is pushed in, the plunger moves against the action of spring J_a, causing the lip or lug P_a to engage the end of one or other of the cooperating racks R1 or R2, depending upon which one is nearest. If rack R1 is engaged, as it is about to be in the position pictured in Fig. 13, the rack will move to the right and gear A_b will be rotated clock-wise by the meshing teeth of the rack and gear. Rack R2 will simultaneously move to the left until further movement is arrested by the engagement of its outer end with the lip or lug P_a. Figs. 14 and 15 show plunger G_b in this final tuned-in position. It will be observed that this action is identical to that described in connection with Figs. 1 and 2 with the exception of the fact that the operating member and racks move longitudinally instead of in an arc.

When the device of Figs. 9 and 10 is modified so that all the parts move in straight lines rather than in arcs, bars 72 and 73 are placed on the ends of the racks, or may be formed from the same pieces of metal. Gear segments C and C_d and bar 72 then become a single integral piece, as do segments D and D_b and shoulder bar 73. The adjustable segments U₁ and U₂ are also replaced by racks meshing with gear 66, or the three adjustable toothed members may be replaced by an angularly adjustable tappet member similar to that used in the device of my Patent No. 2,108,538, issued February 15, 1938, and reissued August 16, 1938, as Patent No. Re. 20,827.

A modification such as the first one mentioned in the preceding paragraph is shown in Figs. 17 to 20, inclusive. Shaft B, which must be operatively connected to the condenser shaft, is journaled in the two end plates 14a and 7a. This shaft carries two gears A₃ and A₄ rigidly attached thereto just inside the end plates 14a and 7a, Fig. 19. Racks R₃ and R₄ mesh with gear A₃, and a similar pair of racks R₅ and R₆, Fig. 19, mesh with the opposite gear A₄ at the other side of the tuner mechanism. The narrowed forward end of rack R₃ moves in a slot 88, Fig. 20, in cross-member 89, and the corresponding end of rack R₄ moves in slot 90. Cross-member 89 provides two similar slots 91 and 92 for the forward ends of racks R₅ and R₆. Racks R₃ and R₄ are provided respectively with slots 93 and 94 to slidably receive the lugs 95 and 96, formed from the stock of the end plate 14a. Similar lugs are formed on end plate 7a for corresponding slots in rack members R₅ and R₆, one of these lugs, 97, being visible in Fig. 19.

Racks R₃ and R₅ are tied together by bar 72a, and a similar shoulder bar 73a joins racks R₄ and R₆ into a single integral unit.

Fig. 19 shows four operating assemblies, or push-button devices, for positioning the shoulder bars 72a and 73a, although obviously any number may be used. The shank of plunger 99 is slidably mounted by means of a slot in the cross member 114, and the inwardly extending end of the plunger moves in one of the slots 113 in the cross member 89, Fig. 20. Each of these operating assemblies comprises a body portion 99 carrying a boss or bushing 69c, Fig. 19, to journal a short shaft 67a on one end of which is rigidly mounted a gear 66a. This short shaft is held in place longitudinally by a nut, shoulder of peened-over portion 68a at its opposite end. Two racks R₇ and R₈ mesh with gear 66a at diametrically opposite points, and are kept in mesh by the flat-headed pins or rivets 100, reduced portions of which pass through the supporting body member 99, the ends being peened-over as shown in Fig. 19. Slots 101 and 102 slide along these rivets or pins when racks R₇ and R₈ move rectilinearly for adjustment purposes. The slots 112 in plate 89 are made large enough to clear the protruding portions of racks R₇ and R₈ when the plunger is pushed inwardly.

Two lugs 104 and 105 are formed on each supporting member or plunger 99. These are threaded to receive the long set-screw 103, which is also threaded into the boss or bushing 69c, Fig. 19, where the end of the screw engages the short shaft 67a which carries gear 66a.

The outer end of the supporting body 99 of the plunger assembly is reduced as shown at 98, Fig. 17, to carry an operating button which is slotted to fit over the said end.

The various operating assemblies or plungers

of this modification of my invention may be preset for desired broadcasting stations in much the same manner described in connection with the device of Figs. 9 to 12, inclusive. The operating button is first removed from the particular plunger that is to be adjusted, and the set-screw is then released to permit the short shaft 67a with its associated gear 66a to turn freely, thus permitting the racks R7 and R8 to move longitudinally. The desired station is then tuned in by means of the regular manual knob (not shown), causing the shaft B and the attached gears A3 and A4 to assume a definite angular position. This in turn causes definite rectilinear positions to be assumed by racks R3, R4, R5 and R6 and the associated cross-bars 72a and 73a. The plunger assembly is then pressed in, and since the racks R7 and R8 are free to move longitudinally, they take the position of the cross bars. Set screw 103 is then again tightened and button ha placed back on the reduced end 98 of the plunger body-member 99. Regardless of subsequent angular positions of the shaft and rectilinear positions of the cross bars and racks, the mere pressing in of the pre-set plunger assembly will cause the shaft B to assume the proper angular position for the broadcasting station for which the racks R7 and R8 have been adjusted.

Fig. 21 illustrates a previously mentioned further modification in which the racks R7 and R8 and gear 66a are replaced by a tappet member or cam 106. In the adjusting or setting process, the end portions 107 and 108 of cam 106 assume angular positions corresponding to the longitudinal positions of the racks R7 and R8 in Fig. 17. This cam is locked in adjusted position by a pivoted member 109 which is rotatably mounted against the body of the plunger 111 by means of the rivet 110. Screw 103a clamps this pivoted member against the cam or tappet, but permits the cam to be angularly adjusted when the screw is loosened. The end plates of this embodiment (only one of which is shown) are tied together by the front cross plate 124 and a rod 123. The racks that mesh with the gears carried by the shaft B each have two slots, rack R9 being shown with slots 116 and 117 on opposite sides of the cross bar 125. Slot 117 moves astride lug 118 formed on plate 126, and slot 116 slides on a similar lug not shown. The slots 119 and 120 in the companion rack R10 move respectively on lugs 121 and 122 also formed on the end plate 126.

Whenever straight racks are used, guides of some kind must of course be supplied. Inasmuch as such guides must necessarily have some play, I prefer the forms of the invention shown in Figs. 1 and 2 and 9 to 12, as the pivoted operating arms and segments are much more accurate in their operation. The use of racks, however, makes a very flat, compact device.

In any of the illustrated or described variants, however, the fact that the operating element pushes the toothed members toward the gears with which they mesh, and moves in a parallel path behind the toothed member that is pushed, produces a more accurate and compact device than anything in the prior art that is dependent upon reciprocally movable toothed members. In one form of tuner used in the past, oppositely moving racks, meshing with an intermediate gear, were employed, but the racks were pulled, rather than pushed, and while the racks moved in straight lines, the operating member moved in an arc—all of which resulted in a bulky and

much less accurate device than the tuners herein described in which all the reciprocating parts move in the same, or parallel, paths with the pressure of the operating means exerted toward the rotatable shaft.

When all the reciprocating parts are pivoted, an arcuate portion like G, Figs. 1 and 9, terminating in an operating button, produces the practical equivalent of a push-button controlled device; and the stem G of each push-button requires an opening in the escutcheon only large enough to clear the stem, which is superior from an appearance standpoint to the long slots that are required by the usual type of operating levers.

Various other modifications are possible without departing from the spirit and scope of the invention, and these will readily suggest themselves to those skilled in the art.

My claims are:

1. In a mechanism for angularly positioning a control of a radio device, a combination including: a rotatable shaft; a second shaft; a pinion gear mounted on said first shaft; an external gear segment pivoted on said second shaft and meshing with said pinion gear; an internal gear segment pivoted on said second shaft and meshing with said pinion gear; and an operating means pivoted on said second shaft; each of said gear segments having an abutment adapted to be engaged by said means; said operating means adapted to engage one of said abutments and rotate said pinion gear and shaft to an angular position at which rotation is arrested by the collision of said means and the oppositely moving other abutment.

2. In a mechanism for angularly positioning a control element, a combination including: a rotatable shaft; two pinion gears fixed upon said shaft; a second shaft; a pair of internal gear segments rotatably mounted upon said second shaft and each meshing with a different one of said gears; a connecting abutment member between said internal gear segments; a pair of external gear segments rotatably mounted upon said second shaft and each meshing with a different one of said gears; a connecting abutment member between said external gear segments; and a plurality of operating devices each comprising adjustable means adapted upon movement of said device toward said shaft to engage one of said abutment members and thereby rotate said gears and shaft to an angular position at which rotation is arrested by the collision of the other abutment member with said adjustable means, said angular position predetermined by the adjustment of said means.

3. In a mechanism for angularly positioning a control of a radio device, a combination including: a rotatable shaft; a first gear mounted on said shaft; a first pair of reciprocally movable toothed members disposed on opposite sides of said shaft and meshing with said gear; a movably mounted operating element carrying both a pinion gear and a second pair of reciprocally movable toothed members meshing with said pinion gear; and means for holding said pinion gear and said last-mentioned toothed members in adjusted position upon said element; each of said last-mentioned members adapted to engage a different one of said first mentioned toothed members and to effect the rotation of said shaft to an angular position predetermined by the adjustment of said pinion gear and the toothed members meshing therewith.

4. In a mechanism for angularly positioning a control element, a combination including: a rotatable shaft; two pinion gears fixed upon said

shaft; a pair of reciprocally movable instrumentalities each comprising two toothed members and an abutment disposed between and connected to said members, each member meshing with a different gear; said instrumentalities positioned on opposite sides of said shaft; and a plurality of operating devices each comprising a movably mounted element carrying a pinion gear and a pair of toothed members each meshing with said pinion gear; and means for maintaining said pinion gear and said last-mentioned toothed members in adjusted position upon said element; each of said last-mentioned members adapted to engage the abutment of a different one of said instrumentalities and effect the rotation of said shaft to an angular position predetermined by the adjustment of said pinion gear and the toothed members meshing therewith.

5. In a mechanism for angularly positioning a control element, a combination including: a rotatable shaft; two pinion gears fixed upon said shaft; a second shaft; a pair of internal gear segments rotatably mounted upon said second shaft and each meshing with a different one of said gears; a connecting abutment member between said internal gear segments; a pair of external gear segments rotatably mounted upon said second shaft and each meshing with a different one of said gears; a connecting abutment member between said external gear segments; and a plurality of operating devices each comprising a movably mounted element carrying a third pinion gear and a pair of toothed members each meshing with said third gear; and means for maintaining said third gear and said toothed members in adjusted position upon said element; each of said toothed members adapted to engage a different one of said abutment members and effect the rotation of said shaft to an angular position predetermined by the adjustment of said third gear and the toothed members meshing therewith.

6. In a mechanism for angularly positioning a control device, a combination including: a rotatable shaft; a gear mounted on said shaft; a pair of reciprocally movable toothed members disposed on opposite sides of said shaft and meshing with said gear; a cover plate; and instrumentalities comprising an operating element protruding through the plane of said cover plate and carrying an angularly adjustable pinion gear and a second pair of reciprocally movable toothed members each meshing with said pinion gear; and means accessible from the front of said plate for affixing said pinion gear and the toothed members meshing therewith in adjusted position; each of the toothed members in said last-mentioned pair adapted to engage a different one of the toothed members in said first-mentioned pair and to effect the rotation of said shaft to an angular position predetermined by the adjustment of said pinion gear and the toothed members meshing therewith.

7. In a mechanism for angularly positioning a control device, a combination including: a rotatable shaft; two pinion gears fixed upon said shaft; a pair of reciprocally movable instrumentalities each comprising two toothed members and an abutment disposed between and connected to said members, each member meshing with a different gear; said instrumentalities positioned on opposite sides of said shaft; a cover plate; and a plurality of movably mounted assemblies each comprising an operating element protruding through the plane of said cover plate and carrying an an-

gularly adjustable third pinion gear and a pair of reciprocally movable toothed members each meshing with said third gear; and means accessible from the front of said plate for affixing said third gear and the toothed members meshing therewith in adjusted position; each of said last-mentioned toothed members adapted to engage said abutments successively and to effect the rotation of said shaft to an angular position predetermined by the adjustment of said third gear and the toothed members meshing therewith.

8. In a mechanism for angularly positioning a control of a radio device, a combination including: a first rotatable shaft having a threaded portion and a transversely extending hole; a plurality of gears independently angularly adjustable on said first shaft; spacers between said gears; a plurality of pairs of reciprocally movable toothed members, the members of each pair disposed on opposite sides of said first shaft and each pair meshing with a different gear; a first gear free to rotate on said first shaft but constrained against axial movement; a threaded element mounted on the threaded portion of said first shaft and adapted to apply pressure to said collars and adjustable gears; means for transmitting rotary motion from said first gear to said element; a second rotatable shaft disposed at right angles to said first shaft and adapted to be longitudinally moved so that one end thereof extends into the hole in said first shaft; a second gear affixed on said second shaft and adapted to engage and rotate said first gear; manually rotatable means for turning said second shaft; and a plurality of operating instrumentalities each individual to one of said pairs of toothed members and adapted upon movement toward said first shaft to push one of the members of said last-mentioned pair and effect the rotation of the associated gear and said first shaft to a position in which rotation is arrested by the collision of said instrumentality and the other member of said last-mentioned pair, said position predetermined by the angular adjustment of said associated gear.

9. In a mechanism for positioning a control of a radio device, an operating means for moving said control during an operating stroke of said means in one direction, said means comprising a lever having an arcuate depending arm adapted to move in a circular path substantially concentric with its curvature, said arcuate arm having an external end adapted for engagement by the operator's finger; and means for pivoting said lever at an upwardly extending end thereof so that said external end moves in a substantially downward direction during said operating stroke.

10. A mechanism for operating a radio tuning apparatus, including: a rotatable control element; positionable means comprising a pair of oppositely and simultaneously movable parts operatively connected to said element and adapted to move in parallel paths on opposite sides thereof; and an operating device carrying a pair of separate tappet members for engaging said parts successively upon movement of said operating device in one direction; said operating device also comprising means for operatively inter-connecting said tappet members in such a manner that they may be moved simultaneously in opposite directions in parallel paths for adjustment purposes.

11. Means for exerting a longitudinal thrust against the angularly adjustable elements on a control shaft of a device for actuating a radio

tuning apparatus, said means including: a threaded portion on said shaft; a rotatable member threaded on said threaded portion; a first gear on said shaft and rotatable relative thereto; means for restraining said first gear against longitudinal movement on said shaft; means for transmitting rotary motion from said first gear to said rotatable member; and means for manually rotating said first gear, said latter means comprising a second shaft and a second gear mounted thereon, said second shaft mounted so that said second gear may mesh with said first gear.

12. Means for exerting a longitudinal thrust against the angularly adjustable elements on a control shaft of a device for actuating a radio tuning apparatus, said means including: a threaded portion on said shaft; a rotatable member threaded on said threaded portion; a first gear on said shaft and rotatable relative thereto; means for restraining said first gear against longitudinal movement on said shaft; means for transmitting rotary motion from said first gear to said rotatable member; means for manually rotating said first gear, said latter means comprising a second shaft and a second gear mounted thereon, said second shaft mounted so that said second gear may mesh with said first gear; and means for immobilizing said first shaft.

13. Means for exerting a longitudinal thrust for clamping purposes against the angularly adjustable elements on a control shaft of a device for actuating a radio tuning apparatus, said means including: a threaded portion on said shaft; a first rotatable member threaded on said threaded portion; a second member on said shaft and rotatable relative thereto; means for restraining said second rotatable member against longitudinal movement on said shaft; means for transmitting rotary motion from said second member to said first member; and manually operable means for rotating said second rotatable member.

14. Means for exerting a longitudinal thrust for clamping purposes against the angularly adjustable elements on a control shaft of a device for actuating a radio tuning apparatus, said means including: a threaded portion on said shaft; a first rotatable member threaded on said threaded portion; a second member on said shaft and capable of rotation relative thereto; means

for transmitting rotary motion from said second member to said first member; means for restraining said second member against longitudinal movement on said shaft; means for immobilizing said shaft in certain angular positions thereof; and manually operable means for rotating said second member relative to said shaft when the shaft is immobilized.

15. Means for exerting a longitudinal thrust for clamping purposes against the angularly adjustable elements on a control shaft of a device for actuating a radio tuning apparatus having a front panel, said means including: a threaded portion on said shaft; a first rotatable member threaded on said threaded portion; a second member on said shaft and rotatable relative thereto; means for transmitting rotary motion from said second member to said first member; means operable from the outer side of said panel for rotating said second member; and means surrounding said shaft and interposed between said first rotatable member and said angularly adjustable elements for transmitting pressure from said first rotatable member to said elements.
